UNITED STATES PATENT OFFICE.

THERÈSE REINHERZ, OF MUNICH, GERMANY.

METHOD OF PRESERVING PLANT-LEAVES, FLOWERS, BUTTERFLIES, AND THE LIKE.

1,076,786.

Specification of Letters Patent.

Patented Oct. 28, 1913.

No Drawing.

Application filed March 3, 1913. Serial No. 751,717.

To all whom it may concern:

Be it known that I, THERÈSE REINHERZ, citizen of Germany, residing at Munich, Bavaria, Germany, have invented certain new and useful Improvements in the Method of Preserving Plant-Leaves, Flowers, Butterflies, and the like; and I do hereby declare the following to be a full, clear, and exact description of the invention, such as will enable others skilled in the art to which it appertains to make and use the same.

Various methods are known for preserving leaves or green plants, as for example by boiling and treatment with lime, but these methods are not applicable to more sensitive vegetable products, that is to say flowers, for the preservation of which treatment with spirit or ether has been proposed, but is too expensive for general use. A different type of treatment, which has been proposed and is also applicable to butterflies and the like, consists in coating the object on one side with a liquid mass which subsequently solidifies, so as to afford a more or less rigid support, and subsequently dipping the object into a mass adapted to form thereon a coating which likewise solidifies and thus envelops the object with a protective film or skin. This method has not come into general use owing to lack of suitable materials for carrying it into effect. The coating of the object, after drying it, with a mixture of linseed oil varnish and gluey matter has also been proposed. Mixtures of gelatin, glycerin and oil have been used for producing air-tight coverings for flesh, fruit and the like.

My invention consists in a simple and cheap method of preserving flowers, leaves, butterflies and the like by means of a coating which is applied to one side only of the object to be preserved, and does not affect the appearance, more particularly the color, of the visible surface of the specimen. To this end I use a concentrated aqueous solution of a colloid substance such as gelatin, white glue or the like, mixed with an oily substance such as castor oil, liquid paraffin or the like, and with glycerin, the colloid substance and oily substance being in about equal parts, but the proportion of glycerin being equal to only about one quarter of the

proportion of oil. To this mixture I add carbonate of magnesium and Venetian turpentine. The proportion of water depends on the nature of the specimen, delicate flowers require a thinner solution than more robust specimens. It will be understood that I may use a mixture of oils, for example castor oil mixed with paraffin. This mixture I apply to the reverse surface of the specimen.

The gelatin, glue or the like sets and gives the requisite mechanical support, the oil preserving the suppleness of the specimen. The glycerin acts to prevent brittleness, and the carbonate of magnesium, of which I may use about one fifth of the weight of the colloid substance, thickens and whitens the mixture and preserves the shape of the specimen. The Venetian turpentine assists in binding the mixture to the specimen. After application of the mixture the specimen is dried.

In general the proportions of the ingredients used for the preserving mixture vary somewhat according to the nature of the specimens. The thicker, heavier flowers require stronger solutions than delicate flowers, and regard must be had to the amount of water or oil already present in specimen.

No special skill is required for applying the mixture; it can for example, be used by nursery gardeners to preserve flowers, grown for sale, from destruction by frost. It can also be used by collectors in uncivilized regions for preserving specimens for scientific purposes.

What I claim as my invention and desire to secure by Letters Patent of the United States is:—

The method of preserving flowers, leaves, butterflies and like specimens, which consists in applying a coating consisting of a mixture of colloid matter, oily matter, glycerin, carbonate of magnesium and Venetian turpentine.

In testimony whereof I hereunto affix my signature in the presence of two witnesses.

THERÈSE REINHERZ.

Witnesses:

OTTO SAILER,
A. V. W. COTILE.
